US0D1059570S

(12) United States Design Patent (10) Patent No.: US D1,059,570 S
(45) Date of Patent: * Jan. 28, 2025

(54) FAN

(71) Applicant: Delta T, LLC, Lexington, KY (US)

(72) Inventors: Gregory Willis Peterson, Nicholasville, KY (US); Vance Elliot Willis, Nunnelly, TN (US); David Matthew Ladnier, Versailles, KY (US); Richard Downey, Danville, KY (US); Edmundo Monti Cortez, Lexington, KY (US); Brian Michael Borgel, Georgetown, KY (US)

(73) Assignee: DELTA T, LLC, Lexington, KY (US)

() Term: 15 Years

(21) Appl. No.: 29/738,780

(22) Filed: Jun. 19, 2020

(51) LOC (15) Cl. 23-04

(52) U.S. Cl.

USPC D23/377

(58) Field of Classification Search

USPC D26/59; D14/370, 377, 385, 411

CPC F04D 25/088

See application file for complete search history.

(57) CLAIM

The ornamental design for a fan as shown and described.

DESCRIPTION

The sole FIGURE is a bottom view of a fan, showing our new design.

The broken lines illustrate portions of the fan that form no part of the claimed design.

Broken jagged break lines shown on the fan depict a symbolic break in length and form no part of the claimed design.

1 Claim, 1 Drawing Sheet
